Inventor:

Fred S. Carr,
by Emery Barth Jameson-Vanney
Attnys

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

Application filed February 26, 1925. Serial No. 11,692.

This invention aims to provide an improved carpet fastener for securing rugs, carpets and the like to floors.

In the drawings, which illustrate two preferred embodiments of my invention:

Figure 1 is a plan view of a portion of a carpet, showing the underlying fastener parts in dotted lines;

Fig. 2 is a section on the line 2—2 of Fig. 1, being partly in elevation;

Fig. 3 is a plan view of the socket before attachment to the carpet;

Fig. 4 is a plan view of the prong-presenting and spring-positioning member;

Fig. 5 is a section on the line 5—5 of Fig. 3;

Fig. 6 is a side elevation of the prong-presenting and spring-positioning part shown in Fig. 4;

Fig. 7 is a plan view of the second form of socket; and

Fig. 8 is a section on the line 8—8 of Fig. 7.

Referring to the drawings, I have shown a carpet fastener which includes a stud secured to the floor of an automobile, or the like support, and a socket secured to a carpet or the like for engagement with the stud to hold the carpet in place relative to the floor.

The stud, as illustrated, is substantially as shown and described in the United States Letters Patent No. 1,433,783, issued October 31, 1922, to Carr Fastener Company, assignee of Moses F. Carr. This stud, as illustrated in Fig. 2, includes a socket-engaging part 1 secured to the floor 3 by the attaching screw 2 substantially as set forth in the above-mentioned Letters Patent.

The socket, as illustrated, is somewhat similar to the one shown and described in the United States Letters Patent No. 1,535,981, issued April 28, 1925, to Carr Fastener Company, assignee of Fred S. Carr, and differs therefrom only as to the location and supporting of the prongs for attaching the socket to the carpet.

This socket, as illustrated, comprises a bottom plate 4 having a stud-receiving aperture 5 therethrough to permit passage of the head of the socket-engaging part 1 of the stud. The bottom plate also presents at its periphery an upstanding wall 6 which provides a central recess in the bottom plate 4 to receive the generally circular spring 7

which normally intersects the stud-receiving aperture 5. This spring 7 is held in position relative to the bottom plate 4 by a spring-retaining dome-shaped plate 8 resting, at its outer periphery, upon the bottom plate 4 and presenting a plurality of upstanding attaching prongs 9.

The spring-retaining plate 8 is secured to the bottom plate 4 by a plurality of lugs 10 pressed from the upstanding wall portion 6 of the bottom plate and bent inwardly and downwardly between the upstanding attaching prongs 9, as best illustrated in Figs. 2 and 3. To strengthen the wall 6, which is somewhat weakened by removal of the material for the lugs 10, I have provided a continuous ring portion 11 which extends outwardly (Figs. 3 and 5) from the upper periphery of the upstanding wall 6.

The socket is secured to the carpet 12 by the prongs 9 which engage the warp and weft threads thereof in substantially the same manner and for the same purposes as set forth in the above-mentioned Patent No. 1,535,981.

In this instance, however, the prongs are formed from the spring-retaining plate 8 and are bent outwardly and downwardly over and through the warp and weft threads of the carpet (Fig. 2) thereby to grip the web of the carpet between the ring portion 11 and the prongs 9. The ring portion 11 not only provides a smooth surface against which the carpet may be pressed by the prongs, but also supports and strengthens the prongs to such an extent that it is practically impossible for them to be bent out of shape or broken by the weight of a person standing upon the carpet directly over the fastener socket.

The ring portion 11 also prevents slipping of the warp or weft threads over the free ends of the hook-shaped portions of any of the attaching prongs, because the threads are squeezed tightly between the prongs 9 and the ring portion 11.

Engagement of the socket with the stud is effected in the usual manner by pressing upon the socket until the head 1 of the stud passes through the apertures in the bottom plate 4 and spring-retaining plate 8, thereby permitting the spring 7 to engage the neck of the stud.

Disengagement of the socket from the stud is effected by grasping the edge of the carpet 110

adjacent the socket and pulling upwardly thereupon.

Referring to Figs. 7 and 8, I have shown a fastener socket substantially as shown and 5 described relative to the first construction illustrated, except that the attaching prongs 9 are formed from the center of the spring-retaining piece 8 and extend upwardly therefrom between the outer periphery and the 10 aperture 5 through which the head of the stud passes. These prongs, as illustrated, are therefore formed in such a manner that the spring-retaining piece may be made much 15 cheaper than the one shown in connection with the first form because of the saving of material.

While I have shown and described two embodiments of my invention, it will be understood that I have done so for purposes of 20 clarification only and that my invention is best defined in the following claims.

Claims:

1. A fastener socket comprising a body portion providing a stud-receiving aperture 25 surrounded by resilient stud-engaging means, a wall at the outer periphery of said body portion adapted to be seated against the under side of a support and a plurality of attaching prongs extending upwardly from 30 said body portion between the inner periphery of said wall and the resilient stud-engaging means, the bases of said prongs being located in a plane substantially below the plane of the upper face of said wall, thereby 35 to permit the bend of said prongs to begin at points below the plane of said wall when said prongs are clinched into engagement with the support.

2. A carpet fastener socket comprising a 40 casing presenting a stud-receiving aperture of fixed dimensions, a stud-engaging spring intersecting said aperture, a ring portion at the periphery of said casing, and a plurality of attaching prongs extending upwardly 45 from said casing at points between said spring and said ring portion and below the plane of said ring portion, said prongs adapted to be bent outwardly over said ring

portion to engage the warp and weft threads of a carpet, thereby providing hooks 50 which arch entirely over the ring portion so as to be supported by said ring portion when the carpet is stepped upon directly over the socket.

3. A carpet fastener socket comprising, in 55 combination, a casing presenting a stud-receiving aperture, a spring intersecting said aperture for engagement with a stud, spring-positioning means assembling said spring with said casing and attaching means 60 standing from and integral with said spring-positioning means for securing said socket to a carpet.

4. A carpet fastener socket comprising, in combination, a casing presenting a stud-receiving aperture, a spring intersecting said aperture for engagement with a stud, spring-positioning means for positioning said spring relative to said aperture and a plurality of attaching prongs extending upwardly from said positioning means and adapted to be curved outwardly and downwardly over the periphery of said casing thereby to provide hooks for engagement 70 over the warp and weft threads of the carpet, the threads being gripped between the prongs and the periphery of the socket.

5. A carpet fastener socket including a casing, a stud-engaging spring member, a spring-positioning member, means integral 80 with said casing for securing said spring-positioning member thereto, and a plurality of attaching prongs pressed from said spring-positioning member for securing said casing to a carpet.

6. A carpet fastener socket including a dish-shaped plate having an upstanding wall providing a central recess in said plate, a contractile and expansible spring for gripping a cooperating stud and a separate 90 prong-presenting and spring-retaining part secured to said plate and surrounded by said wall.

In testimony whereof, I have signed my name to this specification.

FRED S. CARR.
